CLIP FOR GOLF BAGS

Andrew S. Petersen, 117 Barranca St.,
Santa Barbara, Calif. 93105

Continuation-in-part of design application Ser. No. 6,440,
Mar. 30, 1967. This application Sept. 16, 1968, Ser.
No. 13,547

Term of patent 14 years

Int. Cl. D21—03

U.S. Cl. D34—5

FIG. 1

FIG. 3

FIG. 1 is a side elevation view of a clip for golf bags, showing my ornamental design.

FIG. 2 is a front elevation view of the clip of FIG. 1.

FIG. 3 is a bottom view of the clip of FIG. 2.

This application is a continuation-in-part of my design application D. 6,440 filed Mar. 30, 1967, now abandoned.

I claim:

The ornamental design for a clip for golf bags, as shown and described.
